UNITED STATES PATENT OFFICE.

NIELS C. ANDERSEN, OF CHICAGO, ILLINOIS, ASSIGNOR TO THE GOSS PRINTING PRESS CO., OF CHICAGO, ILLINOIS, A CORPORATION OF ILLINOIS.

DELIVERY APPARATUS FOR PRINTING PRESSES.

Application filed May 12, 1927. Serial No. 190,926.

My invention relates to delivery apparatus for printing presses arranged for separating into unit piles the newspapers coming from a press as the completed papers are taken from the folder and placed one at a time by the ordinary fly device upon a set of delivery belts. It is the object of my invention to provide in an apparatus of this type an improved form and arrangement of parts adapted to act at timed intervals upon one of the papers for causing it to assume a slightly different position on the belts from that of the remaining papers, the parts being timed so that one paper out of every unit number of successive papers is so changed in position whereby an operator is enabled readily to take the papers from the belts in unit piles or bunches.

It is one of the objects of my invention to provide a construction of this type which shall be suitable for use in connection with newspapers of varying size and weight and so arranged that regardless of the number of sheets in the folded sections the delivery mechanism shall operate satisfactorily at the timed intervals for displacing the papers in substantially a uniform manner for the separation of the papers into such unit piles.

For accomplishing this result, it is one of the objects of my invention to provide means adapted by a directly forward movement to act on the folded newspaper while in contact with the fly for moving the paper forward with respect to the previously released papers, being adapted preferably to give the paper a light blow in substantially the same direction as that in which the paper is subsequently carried by the belts for causing the paper to clear the fly. It is one of the objects of my invention to provide means of this type in which a pusher device or kicker has substantially a straight-line motion for effecting the changed position of the paper acted upon, in which the extent of the movement of the kicker device can be controlled and changed, in which the direction of the movement of the kicker device can be adjusted, in which the angular position of the contact face of the kicker device can be adjusted, in which such contact member of the kicker device can be adjusted vertically with respect to the de-

vice as a whole, and in which the kicker device and its associated parts can be adjusted vertically as a unit.

It is another object of my invention to improve devices of this type in sundry details hereinafter pointed out. The preferred means by which I have accomplished my several objects are illustrated in the drawings and are hereinafter specifically described. That which I believe to be new and desire to cover by this application is set forth in the claims.

In the drawings,—

Fig. 1 is a side view of a portion of a printing press provided with my improved apparatus, some of the parts being omitted for clearness of illustration and other parts being broken away.

Fig. 2 is a vertical cross section through the mechanism of Fig. 1, being taken substantially at line 2—2 of Fig. 1.

Fig. 3 is a view on an enlarged scale showing a portion of the structure as seen in Fig. 2, and showing also certain of the parts which are broken away in Fig. 2.

Fig. 4 is a more or less diagrammatic view showing a portion of the parts of Fig. 2 and being partially broken away, some of the parts being in section as taken at the line 4—4 of Fig. 2.

Fig. 5 is a view similar to Fig. 4 but showing a different phase of the operation of the parts.

Fig. 6 is a view similar to Fig. 5 but showing an adjusted position of certain of the parts; and

Fig. 7 is a diagrammatic view showing the arrangement of the papers on the belts.

Referring now to the several figures of the drawings in which corresponding parts are indicated by the same reference characters.—10 indicates the frame-work of a printing press of any suitable type comprising a folding cylinder 11, a collecting cylinder 12 and fold-laying rollers 13 and 14. The folding and collecting apparatus are to be of approved type for delivering successively below the fold-laying rollers 13 and 14 complete folded papers or sections. As is well understood, the paper or section delivered by the folder varies in practice to a very large extent in the number of sheets folded together and consequently in the weight of the paper or sec-

tion. Inasmuch as the mechanism so far referred to and illustrated diagrammatically in Fig. 1 forms in and of itself no part of my present invention, it is believed to be unnecessary to describe it in further detail herein.

Directly below the rollers 13 and 14 in the construction illustrated, there is mounted in the frame 10 a shaft or bar 15 held rigidly in position for supporting parts of my improved mechanism. Upon the bar 15 I have mounted a plurality of guide bars 16, in the construction shown two of such bars being shown. The bars 16 are supported at their lower end portions by means of heavy sleeves 17 which are held nonrotatably in position upon the bar 15 by means of set screws 18. The upper ends of the bars 16 extend into grooves 13^a in the face of the fold-laying roller 13, as is clearly indicated in Figs. 1 and 2, the arrangement being such that the papers delivered between the rollers 13 and 14 pass downwardly along the face of the bar 16 at the right in Fig. 1.

Upon a driven shaft 19 adjacent to the guide bars 16 are mounted a plurality of rotary fly devices 20 of well-known type, such fly devices comprising arms 21 which are rotated in clockwise direction about the shaft 19 as shown in Fig. 1 for movement opposite an offset portion 22 provided in the guide bar 16, the arms 21 being moved downwardly and toward the left with respect to the guide bars 16 as illustrated in said Fig. 1. In the construction shown three of the fly devices 20 are provided.

Below the fly devices 20, I have provided a receiver for the papers coming downwardly along the faces of the guide bars 16, such receiver in the construction shown being in the form of endless belts 23 mounted movably in position upon pulleys 24 revolvably mounted upon the frame-work, the portions of the belts and the corresponding pulleys 24 at the right in Fig. 1 being omitted from the drawing for clearness of illustration. The arrangement is such that the upper plies of the belts 23 are movable toward the right in Fig. 1, being driven by power applied to a shaft 25 upon which the pulleys 24 are mounted as illustrated in Figs. 1 and 2. The belts 23 are so arranged as to provide suitable support for the papers coming from the press for arranging the papers in series thereon in somewhat the manner illustrated in Fig. 7. Shields or guides 26 of any suitable type are provided at opposite sides of the machine for holding the papers from sliding transversely from the belts 23, such guides 26 being supported in position by means of brackets 27 of suitable type mounted at their lower ends upon the shaft or bar 15.

The operation of all of the parts so far described will be readily understood by those familiar with the art. The belts 23 are to be

driven at any desired speed sufficient for piling the papers in series thereon as they are delivered successively from the fly devices 20. The shaft 19 and the shaft 25, as well as the shafts of the rollers 13 and 14 and the shafts 70 of the cylinders 11 and 12 are to be driven at the desired speed and in the required timed relation from any suitable source of power as is well understood in the art, the speed of rotation of the shaft 25 having a predetermined relation to the speed of rotation of the folder cylinder 11 as hereinafter described.

Coming now to the means adapted in co-operation with the parts above described for separating the papers into unit piles upon the belts 23 or other receiver for the papers, 28 indicates a plurality of brackets rising from the shaft or cross bar 15, being mounted in position upon such shaft by means of sleeves 29 held adjustably in position upon the bar by means of set screws 30, two of such brackets being employed in the construction illustrated. Upon the upper end of the bracket 28, I have provided a slide box 31 which is adjustably mounted upon the bracket by means of a bolt 31^a. Slidably mounted in the slide box 31 there is a slide block 32 provided upon its upper face with an arm 33 having a vertically disposed slot 34 therein.

Pivottally mounted upon the bracket 28 at an intermediate point, there is a lever 35 journaled in position by means of a bolt 36, the upper end of the lever 35 being connected with the arm 33 of the slide block 32 by means of a bolt 37, the bolt 37 being preferably provided with a bearing sleeve 38 loosely mounted thereon within the slot 34. The arrangement is such that upon reciprocation of the lever 35 about the bolt 36 the slide block 32 is moved back and forth along the slide box 31. 105

At its forward end, (at the right in Fig. 5) the slide block 32 is provided with an upwardly extending arm 39 which is adjustably mounted upon the slide block 32 by means of a pin 40 which can be tightened for 110 holding the arm 39 in any adjusted position, the connection between the arm 39 and the slide block 32 comprising a slot 41 in the arm so that the arm can be adjusted vertically with respect to the slide block as 115 well as angularly. The arm 39 is shown in Fig. 6 in adjusted position as compared with the position illustrated in the remaining figures. When the lever 35 is oscillated about the bolt 36, the arm 39 is moved back 120 and forth opposite the offset portion 22 of the adjacent guide bar 16, such movement being in a horizontal direction as shown in Figs. 4 and 5 or being in a direction adjusted slightly from the horizontal when 125 the slide box 31 is held in adjusted position upon the bracket 28 as shown in Fig. 6. The slide block 32 and the arm 39 constitute the kicker device by which a paper at timed intervals is moved out of engagement with 130

the fly device for causing it to assume a changed position upon the belts 23 as hereinafter described.

Coming now to the means for actuating the kicker device at intervals in timed relation to the delivery of the papers from the rollers 13 and 14, 42 indicates a link pivotally connected by means of a bolt 43 with the lever 35 at an intermediate point thereon, the rear end of the link 42 being connected by means of a bolt 44 with the upper end of a lever 45. The connection between the lever 45 and the link 42 comprises a slot 46 in the lever in which the bolt 44 is mounted whereby the effective length of the lever 45 can be adjusted for varying the length of the stroke of the lever 35 and thus varying the length of the stroke of the kicker device. The lever 45 is mounted in position by means of a sleeve 46 upon a rock shaft 47 revolvably mounted in the framework, the lever 45 being held adjustably in position with respect to the shaft 47 by means of a set screw 48. Upon one end of the shaft 47 at the outer face of the standard 10 of the frame-work I have provided an arm or lever 49 carrying upon its upper end a roller 50 adapted to stand in engagement with a rotary cam 51. In Figs. 4, 5 and 6, the arm 49 and the cam 51 are shown diagrammatically by dotted lines in their relative positions even though the section is taken at a point where such parts would not be seen.

As is clearly shown in Fig. 1, the cam 51 is mounted upon the outer end of the shaft 25 by which the cam is rotated. During the operation of the machine, the roller 50 is held in contact with the face of the cam 51. In the construction shown such contact is secured by the provision of a spring 52 connecting the lever 35 with the stationary cross bar or shaft 15 (see Fig. 5), such spring being omitted from some of the figures of the drawings. For permitting a swinging movement of the arms or levers 49 and 45 in clockwise direction in Fig. 4 and a simultaneous swinging movement of the lever 35 in clockwise direction, I have provided depressions 52 in the face of the cam 51, two of such depressions being provided in the construction as illustrated in Fig. 1. Fig. 5 illustrates the changed position of the parts when the roller 50 is brought into engagement with one of the depressions 52 of the cam. The arrangement is such that in the rotation of the cam 51 the parts are permitted to move from the position as shown in Fig. 4 into the position as shown in Fig. 5 and are almost immediately returned to the position as illustrated in Fig. 4. Means is provided as illustrated in Fig. 1 for closing one of the depressions 52 of the cam 51, such means comprising a bar 53 pivotally mounted upon the face of the cam 51 by

means of a bolt 54, the bar 53 being movable about the bolt 54 either into retracted position as shown in Fig. 1 or into position for causing its free end to close or bridge over the adjacent depression 52. The blade or bar 53 is adapted to be held in adjusted position by means of a bolt 55 having a slotted connection with the bar as is clearly shown in Fig. 1.

With the parts in the adjusted position as shown in Fig. 4, and with the papers being delivered successively by the folding mechanism in position to pass downwardly along the right-hand face of the guide bars 16 as illustrated in Fig. 1, and with the fly device 20 rotating in proper timed relation with respect to the delivery of the papers from the folding mechanism, the papers are received by the successively presented arms 21 of the fly device and are directed downwardly and toward the left in Fig. 1 along the guide bar so as to cause the papers to fall lightly into position upon the travelling belts 23. In the delivery of the papers upon the belts the turning movement of the papers toward the right in said Fig. 1 is controlled very largely by the resistance of the air so as to permit the papers to descend easily into proper position upon the belts in substantially the manner illustrated in Fig. 7. When the cam device 51 reaches the position as illustrated in Fig. 5, the roller 50 is permitted to enter the depression 52, causing the kicker device comprising the slide block 32 and the contact arm 39 to move quickly toward the right opposite the lower portion of the fly device 20 and opposite the offset portion 22 of the guide bar 16. The position of the cam device 51 with respect to the shaft 25 is so adjusted by any suitable mechanism not illustrated that the kicked device is brought forward in the desired timed relation with respect to the delivery of the papers so that the kicker device is caused to meet the advance edge of the paper being carried downwardly and toward the left by the arm 21 of the fly device 20, the contact being in more or less the nature of a blow, serving to move the paper out of engagement with the fly device and to project it forwardly (toward the right in Fig. 1) some little distance in advance of the position which the paper would otherwise have had upon the pile of papers on the belt. The arrangement is such that the kicker device is enabled to change the position of one paper as described without materially affecting the position of the paper next previously delivered; the kicker device is also withdrawn from its advanced position in time to prevent any change or any material change in the position of the next following paper delivered to the belts. With the device in operation as described, a single paper 56 (see Fig. 7) is caused to assume a different position upon the receiver belts 23 as compared with the

position of the remaining papers 57 upon said belts. Inasmuch as the cam 51 is driven in the desired timed relation with respect to the rotation of the folding cylinder 11, it follows that a single paper 56 is caused to assume a changed position upon the receiver at the end of the delivery of each unit bunch of papers, the number of papers in such unit being controlled by the speed of rotation of the cam 51 as compared with the number of papers delivered between the rollers 13 and 14. The device 53 will normally be put into operation for closing one of the depressions 52 of the cam 51 when the cylinder 12 is put into operation for collecting as well as for cutting. In such case, only one paper or section will be delivered for each complete rotation of the folding cylinder 11 as compared with the delivery of two complete papers or sections when the cylinder 12 is being used merely as a cutter cylinder and not as a collector cylinder. It will be understood, of course, that the use of the device 53 for closing one of the depressions 52 is not dependent in any way upon the use of the cylinder 12 as a collector, but the ordinary operation is as above described. In the ordinary embodiment of my invention, the shaft 25 and cam 51 are given a single complete revolution for each fifty revolutions of the folding cylinder 11. With the parts driven in such timed relation, and with the device 53 in its retracted position as shown in Fig. 1, with the folding cylinder 11 delivering two papers or sections between the rollers 13 and 14 for each rotation of the folding cylinder, there would be one hundred papers delivered to the receiver belts 23 for each complete rotation of the cam 51. The papers would accordingly be divided into unit piles of fifty upon the belts, the kicker device being actuated twice at each rotation of the cam device.

Whenever, by reason of a change in the weight of the product being delivered, or a change in the class or condition of the paper forming the folded product, or for any other reason, it is desired to adjust the length of the stroke of the kicker device, this can be effected by an adjustment of the bolt 44 along the slot 46 for changing the effective length of the arm or lever 45. When it is desired to change the vertical position of the contact member 39 of the kicker device, such member 39 can be adjusted vertically with respect to the slide block 31 by the adjustment of the slot 41 with respect to the securing pin 40. Whenever it is desired to change the angle at which the contact member 39 stands with respect to the body portion of the kicker device, this also can be effected by loosening the pin 40 for swinging the arm thereabout. When it is desired to adjust the direction of movement of the kicker device slightly, this can be effected by loosening the bolt 31^a so as to permit the slide

box 31 to be swung thereabout in either direction as may be desired. When it is desired to adjust the mechanism as a whole with respect to the flies and the guide bars, this can be effected by loosening the set screws 30 for swinging the brackets 28 slightly about the bar 15 as may be required. As will be readily understood, since the pivot bolt 31^a is in position to stand substantially opposite the pivot bolt 37 when the lever 35 is at the middle of its swing, an adjustment of the slide box 31 about the pivot bolt 31^a affects the position of the kicker device very slightly. It is thus possible to adjust the angular position of the slide box 31, and to adjust the angular position of the contact member 29 of the kicker device without changing to any great extent the limit positions of the kicker device backwardly and forwardly with respect to the guide bars and without changing appreciably the length of the stroke of the kicker device.

I have found in the commercial use of my device that it works very satisfactorily for the purpose for which it is designed, the arrangement being such that the papers are caused to assume the desired changed position upon the belts 23 at timed intervals regardless of the number of sheets of paper making up the section. While I prefer to employ the construction as illustrated in the drawings and as above described, it will be understood that I do not limit the invention to the form shown except so far as certain of the claims are specifically so limited, it being evident that changes might well be made in the form of the device without departing from the spirit of my invention.

I claim:

1. In a delivery apparatus for papers moving forward successively in timed relation, the combination of a receiver upon which such papers are piled, a kicker device, means for mounting the kicker device movably in position for reciprocation back and forth across the face of the receiver, and means actuated in timed relation with respect to the delivery of the papers for moving said kicker device into contact with a paper at timed intervals for causing the paper to have a different position on the receiver as compared with the papers adjacent thereto, the means for mounting and moving the kicker device being so arranged that the kicker device comes into contact with the paper in each instance by a blow on the edge of the paper while moving in a substantially straight-line motion.

2. In a delivery apparatus for papers moving forward successively in timed relation, the combination of a receiver upon which such papers are piled, a rotary fly device to which said papers pass in their movement, a kicker device movable forwardly at the lower portion of the fly device in sub-

stantially the reverse direction as compared with the direction of movement of the arms of the fly device, and means actuated at intervals in timed relation with respect to the 5 delivery of the papers for moving said kicker device in each instance into contact with one of said papers for pushing the paper forwardly out of engagement with the fly device for causing it to assume a different 10 position on the receiver as compared with the papers adjacent thereto whereby the papers on the receiver are divided into unit piles.

3. In a delivery apparatus for papers 15 moving forward successively in timed relation, the combination of a receiver upon which such papers are piled, a kicker device mounted adjacent to said receiver and movable back and forth across the face thereof 20 at an adjustable angle with respect to the receiver, and means actuated at intervals in timed relation with respect to the delivery of the papers for moving said kicker device into contact with corresponding papers of 25 successive unit bunches of papers for causing such contacted papers as delivered to said receiver to have different positions thereon as compared with the remaining papers.

4. In a delivery apparatus for papers 30 moving forward successively in timed relation, the combination of a receiver upon which such papers are piled, slide means mounted above said receiver and adjustable 35 about a horizontal axis with respect thereto, a kicker device slidably mounted on said slide means and movable thereon back and forth across the face of the receiver at an adjustable angle with respect thereto, and means actuated at intervals in timed relation 40 with respect to the delivery of the papers for moving said kicker device on said slide means into contact with one of the papers for causing the paper in each instance to assume a different position on said receiver as 45 compared with the papers adjacent thereto.

5. In a delivery apparatus for papers 50 moving forward successively in timed relation, the combination of a receiver upon which such papers are piled, a kicker device mounted adjacent to said receiver and movable back and forth across the face thereof, and means actuated in timed relation for giving said kicker device an operative stroke 55 of adjustable length into contact with one of said papers for causing such contacted paper in each instance to assume a different position on said receiver as compared with the papers adjacent thereto.

6. In a delivery apparatus for papers 60 moving forward successively in timed relation, the combination of a receiver upon which such papers are piled, a kicker device mounted adjacent to said receiver and movable 65 back and forth across the face thereof,

a lever mechanism of adjustable effective length actuated in timed relation for giving said kicker device an adjustable stroke into contact with one of said papers at intervals for causing such contacted paper in each instance to assume a different position on said receiver as compared with the papers adjacent thereto. 70

7. In a delivery apparatus for papers 75 moving forward successively in timed relation, the combination of a receiver upon which such papers are piled, a kicker device mounted adjacent to said receiver and movable back and forth across the face thereof, a cam rotatable in timed relation with respect to the delivery of said papers, and lever and link mechanism controlled by said cam for giving said kicker device an operative stroke into contact with one of said papers 80 at intervals for causing such contacted paper in each instance to assume a different position on said receiver as compared with the papers adjacent thereto, one of said levers and links being adjustable for varying the length of the stroke of said kicker device 85 to suit it to the size of the papers being operated upon.

8. In a delivery apparatus for papers 90 moving forward successively in timed relation, the combination of a receiver upon which such papers are piled, a kicker device mounted adjacent to said receiver and movable back and forth across the face thereof, a cam rotatable in timed relation with respect to the delivery of said papers, and 95 lever and link mechanism controlled by said cam for giving said kicker device an operative stroke into contact with one of said papers at intervals for causing such contacted paper in each instance to assume a different position on said receiver as compared with the papers adjacent thereto, one of said levers being connected with its co-operating link by a slot and pin connection with the pin adjustable along the slot for 100 varying the effective length of the lever for adjusting the length of the stroke of the kicker device. 105

9. In a delivery apparatus for papers 110 moving forward successively in timed relation, the combination of a receiver upon which such papers are piled, a kicker device mounted adjacent to said receiver and movable back and forth across the face thereof, means for adjusting the angular position of the contact member of the kicker device, and means actuated in timed relation for giving said kicker device an operative stroke into contact with one of said papers for causing 115 such contacted paper in each instance to assume a different position on said receiver as compared with the papers adjacent thereto. 120

10. In a delivery apparatus for papers 125 moving forward successively in timed relation, the combination of a receiver upon 130

- which such papers are piled, a kicker device mounted adjacent to said receiver and movable back and forth across the face thereof at an adjustable angle with respect 5 to the receiver, means for adjusting the angular position of the contact member of the kicker device with respect to the body portion thereof, and means actuated in timed relation for giving said kicker device an operative stroke into contact with one of 10 said papers for causing such contacted paper in each instance to assume a different position on said receiver as compared with the papers adjacent thereto.
11. In a delivery apparatus for papers moving forward successively in timed relation, the combination of a receiver upon which such papers are piled, a kicker device mounted adjacent to said receiver and 15 movable back and forth across the face thereof, means for adjusting the contact member of the kicker device vertically with respect to the body portion of the kicker, and means actuated in timed relation for 20 giving said kicker device an operative stroke into contact with one of said papers for causing such contacted paper in each instance to assume a different position on said receiver as compared with the papers adjacent thereto.
12. In a delivery apparatus for papers moving forward successively in timed relation, the combination of a receiver upon which such papers are piled, a kicker device mounted adjacent to said receiver and 25 movable back and forth across the face thereof, means for adjusting the contact member of the kicker device vertically with respect to the body portion of the kicker device and for adjusting the angular position 30 of the contact member with respect to said body portion, and means actuated in timed relation with respect to the delivery of the papers for giving said kicker device an operative stroke into contact with one of 35 said papers for causing such contacted paper in each instance to assume a different position on said receiver as compared with the papers adjacent thereto.
13. In a delivery apparatus for papers moving forward successively in timed relation, the combination of a guide bar along 40 one face of which said papers pass, a receiver below said guide bar upon which such papers are piled, a kicker device, and means for moving 45 said kicker device at substantially right angles with respect to the adjacent portion of the guide bar across the path of the papers for diverting papers at intervals from their path along the bar for causing 50 such diverted paper in each instance to assume a different position on the receiver as compared with the papers adjacent thereto.
14. In a delivery apparatus for papers 55 moving forward successively in timed relation, the combination of a guide bar along one face of which said papers pass and having an offset portion at an intermediate point, means for guiding the advanced edges of the papers substantially along the offset portion of the guide bar, a receiver below said guide bar upon which said papers are piled, a kicker device below the offset portion of the guide bar, and means for moving 60 said kicker device past said guide bar into contact with the advance edges of papers at intervals for causing such contacted paper in each instance to be diverted from its path along the guide bar and to assume a different 65 position on the receiver as compared with the papers adjacent thereto.
15. In a delivery apparatus for papers moving forward successively in timed relation, the combination of a receiver upon which such papers are piled, a support rising above said receiver and adjustable vertically with respect thereto, a kicker device mounted on said support and movable back and forth across the face of the receiver, and 70 means actuated in timed relation with respect to the delivery of the papers for giving said kicker device an operative stroke into contact with one of said papers for causing such contacted paper in each instance to assume a different position on said receiver as compared with the papers adjacent thereto.
16. In a delivery apparatus for papers moving forward successively in timed relation, the combination of a receiver upon which such papers are piled, a horizontally disposed shaft below said receiver, a curved bracket revolubly mounted on said shaft and rising above said receiver, a set screw for holding 75 said bracket in adjusted position on said shaft for varying the vertical position of the bracket, a kicker device mounted on said bracket and movable back and forth across the face of the receiver, and means actuated in timed relation with respect to the delivery of the papers for giving said kicker device an operative stroke into contact with one of said papers for causing such contacted paper in each instance to assume a different position on said receiver as compared with the papers adjacent thereto.
17. In a delivery apparatus for papers moving forward successively in timed relation, the combination of a guide bar along one face of which said papers pass and having an offset portion at an intermediate point, a fly device rotatably mounted adjacent to the offset portion of said guide bar at the opposite face thereof from that along which said papers pass, a receiver below said guide bar upon which said papers are piled as they pass out of contact with the fly device after being directed along the offset portion of the guide bar by the fly device, a kicker device below 120
- 130

the offset portion of the guide bar, and means for moving said kicker device past said guide bar into contact with the advanced edges of papers at intervals for causing such contacted paper in each instance to be diverted from its path along the guide bar and to assume a different position on the receiver as compared with the papers adjacent thereto.

18. In a delivery apparatus for papers moving downwardly successively in timed relation, the combination of a receiver, means serving normally by engagement with the papers successively as they move downwardly to turn the papers successively from their downward movement into regularly arranged position on the receiver, and means movable forwardly along the face of the receiver at intervals in the operation of the apparatus adapted at each such forward movement to engage one of said papers before it reaches said receiver and to push it forwardly out of engagement with said turning means for causing said paper to take a different position on the receiver as compared with that taken by the papers adjacent thereto.

19. In a delivery apparatus for papers moving downwardly successively in timed relation, the combination of a receiver, a fly device rotating in timed relation to the movement of the papers adapted normally to deposit such papers on said receiver in regularly arranged position thereon, and means movable forwardly along the arms of the fly device at the lower portion thereof at intervals in the operation of the apparatus adapted at each such forward movement to engage a paper in said fly device and to push such paper forwardly out of engagement with the fly device for delivery to the receiver in changed position as compared with the position at which the adjacent papers are delivered to said receiver.

20. In a delivery apparatus for folded papers moving downwardly successively in timed relation with the folded edges in the lead, the combination of a receiver upon which said papers are piled, a kicker device, means serving for mounting said kicker device movably in position above said receiver so as to be movable back and forth along the face of the receiver and serving to hold the kicker device from swinging movement during the movement across the receiver, and means actuated at intervals during the operation of the apparatus for moving said kicker device into contact with a paper during its movement to the receiver and adapted by such contact to move such paper forwardly for causing it to take a different position on the receiver as compared with that taken by the papers adjacent thereto.

21. In a delivery apparatus for folded papers moving downwardly successively in timed relation with the folded edges in the lead, the combination of a receiver upon which said papers are piled, a kicker device, means serving for mounting said kicker device movably in position above said receiver so as to be movable back and forth along the face of the receiver and serving to hold the kicker device from swinging movement during the movement across the receiver, and means actuated at intervals during the operation of the apparatus for giving said kicker device a sharp movement into the path of the papers serving by contact with one of the papers edgewise of the paper during the movement of the paper to the receiver to move such paper forwardly for causing it to take a changed position on the receiver as compared with that taken by the adjacent papers on said receiver.

NIELS C. ANDERSEN.
